FIG. 1

FIG. 2

FIG. 3

FIG. 4

FIG. 5

FIG. 6

FIG. 1 is a perspective view of a housing for an X-ray tube illustrated with port side down and horns directed at an angle of 90° from the port and showing our new design;

FIG. 2 is a side elevational view;

FIG. 3 is an end elevational view, to an enlarged scale, the opposite end being substantially a mirror image thereof;

FIG. 4 is a top plan view;

FIG. 5 is an end elevational view, to an enlarged scale, showing the rotatable horns directed in the same direction as the port; and

FIG. 6 is an end elevational view, to an enlarged scale,

showing the rotatable horns directed at an angle of 180° from the port.

The dominant features of my new design are shown in solid lines in the drawing.

We claim:

The ornamental design for a housing for an X-ray tube, as shown and described.
